PROCESS OF MAKING NITRIC ACID FROM AIR.

No. 814,917.

Specification of Letters Patent.

Patented March 13, 1903.

Application filed March 24, 1901. Serial No. 199,360.

To all whom it may concern:

Be it known that we, ARTHUR PAULING and HARRY PAULING, mining engineer, subjects of the German Emperor, and residents of 5 Bismarck, Westphalia, in the Kingdom of Prussia, German Empire, have invented certain new and useful Improvements in Processes for the Production of Nitric Acid from Air and Like Gaseous Mixtures, of which the 10 following is a specification.

Our invention relates to a process of manufacturing nitric acid from air or other mixture of oxygen and nitrogen.

The process depends upon the well-known 15 fact that air on being heated to at least 1200° centigrade is partially converted into one or more of the oxids of nitrogen. The extent of conversion increases with the temperature according to the well-known equation of 20 the reaction-isochor. At 1700° centigrade, for instance, the quantity of nitric oxid or other nitrogen oxid amounts to about three per cent. according to recent determinations. Although in prior experiments on the production 25 of nitric acid from air the latter has undoubtedly been heated to the temperature stated and even to a still higher degree, the results obtained have not been satisfactory, since it has not been possible to successfully 30 separate the nitrogen oxid from the air. The essential fault of prior methods has been that the highly-heated air has cooled down again gradually, in consequence of which the above-mentioned process of conversion has been re- 35 versed, which, indeed, follows naturally from the equation of the reaction-isochor, which is only applicable to reversible processes. According to our invention this defect has been entirely overcome.

40 In carrying out our process we heat the air or other mixture of oxygen and nitrogen to a very high temperature and then at once chill or cool the resulting nitrous products in the immediate proximity of the place of maximum heating, this cooling being effected so rapidly that reversal of the process of conversion is prevented, so that the nitric oxid or other oxids of nitrogen cannot be decomposed again. Water-vapor is then supplied 45 for the purpose of producing nitric acid. The cooling or chilling can be effected by cooled

metallic or other surfaces or by the injection of cold, indifferent, or neutral liquids or gases or in any other suitable manner. The essential point is that the cooling be effected more 55 rapidly than the oxids of nitrogen which have been formed are decomposed again owing to reversal of the process.

The accompanying drawings illustrate three different arrangements of apparatus 60 suitable for carrying our invention into effect.

Figure 1 is a vertical section of one form of apparatus suitable for the object in view. Fig. 2 is a sectional view illustrating a second arrangement which may be adopted. Fig. 3 65 is a like view illustrating a third arrangement.

Referring to Fig. 1, 1 is a fan by means of which air or some other mixtures of oxygen and nitrogen is forced through a conservér or accumulator of heat 2, previously heated to 70 the desired temperature. The air (or other gaseous mixture) leaves the vessel 2 with great velocity at the outlet 3 and meets the conical jet 4 of atomized cold water issuing from the tank 5. The water jet 4 is immediately converted into steam, and owing to the high degree of absorption of heat (latent heat and heat required to heat the water and steam) the air (or other mixture) is cooled below the injurious limit of temperature. 75 The cooled mixture of air and steam leaves 80 the apparatus at the exit 6 for the purpose of further cooling and condensation of the acid vapors formed.

Referring now to the second arrangement, 85 as shown in Fig. 2, 7 is an alternating-current arc 7, which may advantageously be of about two inches in length. Usually such an arc has a more or less conical shape, as shown by the dotted lines in Fig. 2. The part 7 90 (hatched lines, Fig. 2) forms the actual path or zone of the current between the electrodes 9 and 10, and thus constitutes the source of heat, while the part 8 represents the air heated by the part 7 and under ordinary circumstances ascending in the shape of a cone. 95 11 represents tubes cooled by water or other means located directly above the zone 7, whereby the formation of the part 8 of the electric arc, such as would ordinarily occur, 100 is prevented. The part 8, as a matter of fact, merely indicates that the air highly

heated in the zone 7 gradually cools again in the latter and appears as a flame so long as it is in a state of incandescence. In the case of an arc of approximately the length above 5 stated the part 8 will have a height of about four inches and its temperature gradually diminishes from below upward until the air becomes so much cooled down that this "flame" as such no longer exists. In prior apparatus 10 with such an alternating-current arc the yield of nitric acid has only been about 1.8 per cent. owing to the gradual cooling taking place, even the critical temperature of 1200° centigrade being slowly passed. When 15 water-pipes 11, however, are employed as above, as much as 4.5 per cent. nitric acid can be obtained—that is to say, more than has hitherto been the case with short arcs of small current strength, (sparks, &c.)

20 The arrangement shown in Fig. 3 is very similar to that just described; but in place of pipes 11 cooled by water an atomizer 12 is employed. The nozzle of this device directs into the arc a conical-shaped jet of cold water in a state of fine division or spray immediately above the zone 7 and at right angles thereto.

It must be distinctly understood that we do not in any way restrict ourselves to the 25 employment of the above-described apparatus, as the invention may be carried into effect with the aid of various kinds of plant.

Having thus described our invention, we claim as new—

1. The process of producing nitric acid, 35 consisting in heating a mixture of oxygen and nitrogen to as high a temperature as possible to the exclusion of all cold, and in then at once cooling the resulting nitrous products with all possible suddenness in immediate 40 proximity to the place of maximum heating, the rapidity being such that reversal of the previous action is prevented, substantially as described.

2. The process of producing nitric acid, 45 consisting in heating a mixture of oxygen and nitrogen to as high a temperature as possible to the exclusion of all cold, and in then at once cooling the resulting nitrous products with all possible suddenness in immediate 50 proximity to the place of maximum heating, the rapidity being such that reversal of the previous action is prevented, and in supplying water-vapor to the said nitrous products, substantially as described. 55

In witness whereof we have hereunto signed our names, this 4th day of March, 1904, in the presence of two subscribing witnesses.

ARTHUR PAULING.
HARRY PAULING.
